CLAIM

The ornamental design for a can top, as shown and described.

DESCRIPTION

FIG. 1 is a perspective view of the can top in full lines with a can bottom shown in broken lines representing environmental association matter being for illustrative purposes only and forming no part of the claimed design.

FIG. 2 is a top plan view thereof.

FIG. 3 is a bottom plan view thereof.

FIG. 4 is a front elevational view of the can top.

FIG. 5 is a rear elevational view thereof.

FIG. 6 is a right side elevational view thereof, and,

FIG. 7 is a left side elevational view thereof.
